JOHANN ARTMANN, OF ESSEN-ON-THE-RUHR, GERMANY.

CONTINUOUS DISTILLATION OF TAR.

1,214,259.

Specification of Letters Patent. Patented Jan. 30, 1917.

Application filed October 14, 1909. Serial No. 522,540.

To all whom it may concern:

Be it known that I, JOHANN ARTMANN, a subject of the German Emperor, and residing at Essen-on-the-Ruhr, Germany, have 5 invented certain Improvements in and Relating to the Continuous Distillation of Tar, of which the following is a specification.

My invention relates to the continuous distillation of tar.

According to my invention the individual 10 constituents of the tar are separated continuously during the distillation and likewise in several stills which the tar passes in succession. The tar is not first heated in the 15 stills however, but it is heated preliminarily and supplied at the distillation temperature to the first still, the waste furnace gases of the stills being used for the preliminary heating. Not only is the cost of working 20 diminished in consequence of improved utilization of heat, but above all it is possible to work really continuously owing to the volatile constituents being now separated in the proper manner, pitch of like nature 25 always leaving apparatus.

One constructional form of apparatus for carrying my process into practice is represented by way of example in the accompanying drawing in which—

Figure 1 is a vertical section and Fig. 2 a 30 plan of the apparatus.

The tar, which is first supplied through the condensers in a well known manner for the purpose of preliminarily heating it, as 35 supplied, after water has first been removed from it, to the system of pipes *a* inclosed by masonry, in which system it is heated with the aid of the furnace gases flowing from the furnaces of the stills *b* and *c* so that it 40 enters into the still *b* at a temperature of about 250° C. and here gives off the medium weight and naphthalene oils. The tar then flows into still *c*, gives off the heavy oils and then passes into the non-heated boiler *d* in 45 which the heavier volatile constituents are distilled off by the steam, so that pure pitch is discharged. The volatile constituents are conducted from the stills *b* and *c* and the boiler *d* through the pipes *e*, *f* and *g*, respectively, into the condensers *h*, *i* and *k*, 53 respectively.

I claim:

1. A method of continuously distilling tar, which consists in preliminarily heating the 55 tar above the distillation temperature of the medium weight and naphthalene oils with-

out permitting their distillation, then continuously distilling off said medium weight and naphthalene oils, continuously conducting away the residue of said tar from said region of distillation, then continuously distilling off the heavy oils in said residue, and continuously conducting away from the region of said second distillation the second residue of said tar remaining after said second distillation, and continuously removing from said second residue the heavier volatile constituents thereof, and continuously conducting away the pitch thus remaining, the said heat thus preliminarily imparted to the 70 tar before the distillation thereof being sufficient to enable the said continuous distillation, substantially as described.

2. A method of continuously distilling tar, which consists in preliminarily heating the 75 tar to 250° C., then continuously distilling off from said tar the medium weight and naphthalene oils contained therein, continuously conducting away the residue of said tar from said region of distillation, then continuously distilling off the heavy oils in said 80 residue, and continuously conducting away from the region of said second distillation the second residue of said tar remaining after said second distillation, and continuously removing from said second residue the heavier volatile constituents thereof, and continuously conducting away the pitch thus remaining, said tar being heated only before the distillation of the said medium and 85 naphthalene oils, the said heat preliminarily imparted to the tar being sufficient to enable the said continuous distillation, substantially as described.

3. A method of continuously distilling tar, 90 which consists in first dehydrating the tar, preliminarily heating the tar above the distillation temperature of the medium weight and naphthalene oils without permitting the distillation thereof, then continuously distilling off said medium weight and naphthalene oils, continuously conducting away the residue of said tar from said region of distillation, then continuously distilling off the heavy oils in said residue, and continuously 100 conducting away from the region of said second distillation the second residue of said tar remaining after said second distillation, and continuously removing from said second residue the heavier volatile constituents 105 thereof, and continuously conducting away the pitch thus remaining, the said heat im-

parted to the said tar before the commencement of the first distillation, plus the heat imparted to the residues thereof in said regions of distillation being sufficient for all 5 the distillations thereof, substantially as described.

4. A method of continuously distilling tar, which consists in first dehydrating the tar, preliminarily heating the tar to 250° C., 10 then continuously distilling off the medium weight and naphthalene oils without permitting the distillation thereof, continuously conducting away the residue of said tar from said region of distillation, then continuously 15 distilling off the heavy oils in said residue, and continuously conducting away from the region of said second distillation the second residue of said tar remaining after said sec-

ond distillation, and continuously removing from said second residue the heavier volatile 20 constituents thereof, and continuously conducting away the pitch thus remaining, the said heat imparted to the said tar before the commencement of the first distillation, plus the heat imparted to the residue thereof in 25 said regions of distillation being sufficient for all the distillations thereof, substantially as described.

In testimony, that I claim the foregoing as my invention, I have signed my name in 30 presence of two subscribing witnesses.

JOHANN ARTMANN.
